UNITED STATES PATENT OFFICE.

ABRAHAM GOLDBERG, OF NEW YORK, N. Y.

SKIRT.

1,003,734.

Specification of Letters Patent. Patented Sept. 19, 1911.

Application filed January 14, 1909, Serial No. 472,195. Renewed July 31, 1911. Serial No. 641,661.

To all whom it may concern:

Be it known that I, ABRAHAM GOLDBERG, a citizen of the United States, and a resident of the city of New York, borough of Manhattan, in the county and State of New York, have invented a new and Improved Skirt, of which the following is a full, clear, and exact description.

This invention relates to skirts and like garments, and relates more particularly to wearing apparel of this class which has a waist band, plackets at each side and a back fent, so that the skirt at the waist band is split at three points. Each of the plackets at one edge has a member by means of which the other edge can be removably fastened; the waist band has adjustable elastic straps, each adapted to attach to a fastening member at the free end; the plackets and the fent are preferably provided with clasp fasteners, and the waist band at the fent has a suitable fastener. Each of the plackets, near the lower end, is provided with a pocket, which can be closed by means of suitable clasps or the like.

The object of the invention is to provide a simple, inexpensive and durable skirt, petticoat or the like, which can be easily put on and taken off, the waist band of which is adjustable so that the skirt can be worn by persons having different waist measurements, and which provides pockets for carrying valuables and the like.

The invention consists in the construction and combination of parts to be more fully described hereinafter and particularly set forth in the claims.

Reference is to be had to the accompanying drawings forming a part of this specification, in which similar characters of reference indicate corresponding parts in both figures, in which—

Figure 1 is a perspective view of the upper part of a skirt showing an embodiment of my invention applied thereto; and Fig. 2 is an enlarged transverse section on the line 2--2 of Fig. 1.

Before proceeding to a more detailed description of my invention, it should be understood that the same is applicable to different forms of garments, such, for example, as skirts, petticoats or the like. If so desired, it can even be used in connection with certain forms of trousers or like bifurcated garments. All of the features set

forth above need not be included in a single garment, and certain of the features can be eliminated without departing from the underlying spirit of the invention. 60 For example, the pockets can be dispensed with, or the back fent can be eliminated. These and certain of the other details can be varied in accordance with individual preference and special conditions. 65

Referring more particularly to the drawings, I have shown for example a skirt 10, having a waist band 11, which is split at the sides to form plackets 12, the edges of which are sewed or otherwise finished in any preferred or common manner. At the rear the skirt has a back fent 13, the edges of which are likewise suitably finished. The waist band 11 may be finished in any convenient manner. Near the lower end 75 each of the plackets has a pocket 14, opening at an edge of the placket. The latter has a series of clasps or fasteners 15 of any suitable type. These may consist, as shown for example in the drawings, of the usual 80 clasp fasteners employed with gloves and similar articles, and they may be of any necessary number to permit the placket to be closed from top to bottom. The back fent likewise has a series of similar clasp 85 fasteners 16.

At the upper end each of the plackets has permanently associated therewith a closing member 17, consisting for example, of a hook 18 having at one end a head 19. The 90 head is positioned on the inside of the waist band and the hook projects through the material to the outside of the corresponding placket edge. The other placket edge, at a point opposite the hook, has an eyelet or 95 buttonhole 20, through which the hook can project, as is shown most clearly in Fig. 1, for the purpose of securing the placket edges removably together.

I provide a fastener 21 of any suitable 100 kind, for securing the upper ends of the fent edges together. This fastener may consist, for example, of a hook 22 adapted to engage a retaining bar 23, the hook and the bar being respectively secured at the fent 105 edges.

The waist band at each side of the fent and between the latter and each of the plackets, has sewed or otherwise mounted thereon a sheath 24 fashioned, like the waist band, from suitable flexible material. 110 Within each of the sheaths is positioned an

extensible strap 25, formed preferably from elastic material such as rubber cloth or the like. The straps are sewed or otherwise attached within the sheaths at the ends adjacent to the back fent, and are doubled upon themselves and provided with adjusting buckles 26, by means of which their lengths can be varied. Within the loop of each strap is mounted a catch member 27 consisting preferably of a flat link having an offset 28, which is adapted to engage one of the hooks 18 to attach the strap to the member 17. The stays can be partly elastic and partly inelastic. It will be seen that the members 17 perform double functions. They serve to secure the upper placket edges together and at the same time to attach the free ends of the adjusting straps to the waist band. The elastic straps cause the waist band of the skirt to conform, when suitably adjusted, to the waist of the wearer of the garment. By means of the buckles 26 the straps can be lengthened or shortened as necessary to adapt the skirt for use by persons having different waist measurements. It will be understood too, that the extensible or elastic nature of the straps causes the garment to fit snugly, the material being gathered or Shirred at the waist band adjacent to the straps, when the latter cause the garment to fit a waist smaller in circumference than the normal circumference of the waist band. If so desired, the back fent 13 can be dispensed with, the straps being fastened at the back to the waist band, which is there unbroken. In order to adjust the elastic straps

25, they can be drawn from the sheaths, and after being suitably adjusted, the sheaths can be smoothed out and caused to again envelop the straps.

Having thus described my invention, I claim as new and desire to secure by Letters Patent:

1. A skirt having a placket, a fastener 45 permanently associated with one edge of said placket and adapted to project through the other edge of said placket to secure the edges together, a sheath, and an elastic waistband-adjusting strap in said sheath, 50 said strap having the end remote from said placket permanently attached to the waistband of said skirt, and further, having means at the free end for removably attaching to said fastener. 55

2. A skirt having a placket, a fastener mounted at one edge of said placket, the other edge of said placket having an eyelet arranged to permit said fastener to project therethrough whereby the placket edges can 60 be secured together, and an extensible elastic strap secured at one end to the waist band of the skirt and having a member at the free end adapted to attach removably to said fastener when the same projects 65 through said eyelet.

In testimony whereof I have signed my name to this specification in the presence of two subscribing witnesses.

ABRAHAM GOLDBERG.
